HAND LOOM

Milo O. Gallinger, Hartland, Mich., assignor to
 J. Robert Crouse, Cleveland Heights, Ohio, doing
 business as Cromaine Crafts, Hartland,
 Mich.

Application November 12, 1938, Serial No. 239,962

8 Claims. (Cl. 139—33)

This invention relates to hand operated weaving looms of the floor type.

Looms of this character are somewhat bulky and in schools and other institutions where weaving is taught to a number of persons, the floor space required by the requisite number of looms is a consideration of considerable importance, as is also the cost of the necessary equipment, because as looms have heretofore been constructed an individual loom could be used for only one weaving project at a time so that a loom has been required for each weaver where, as is usual, all of the weaving on a given project is done by one person and the project continues for a considerable period of time.

An object of this invention is to provide a hand loom of the floor type which is so constructed that it can be used successfully and conveniently to carry on several weaving projects within the same period of time. And with respect to this object, the invention consists in the provision of a loom having a separable sub-assembly of parts comprising a warp roll, heddles, heddle frames and rods (or other means for operatively carrying the heddles), a reed and a frame or supporting structure for the other parts of the sub-assembly constructed to permit the entire sub-assembly to be removed as a unit from the main frame of the loom, whereby a single loom provided with a plurality of such separable assemblies, similar to each other and interchangeable in the loom, may be used to carry on a corresponding number of weaving projects by a number of different weavers, the sub-assembly of one weaver together with the work in progress being removed from the main frame of the loom to permit the insertion of another weaver's sub-assembly and work while the latter weaver is making use of the loom.

Another object of the invention is the provision of a loom having a separable sub-assembly, as above described, in which the sub-assembly frame and its fittings are constructed and arranged to facilitate the dismounting of the other parts of the assembly from the normally cooperating parts of the loom and to facilitate the support and handling of the said other parts of the assembly when the assembly is detached from the loom. To this particular end the invention consists in certain features of construction and arrangement of parts which will hereinafter be described in detail.

A further object of the invention is to provide a hand loom having an improved friction device for controlling the unwinding of the warp roller of the loom. With respect to this object, the

invention consists in the provision for the loom of a warp roller having a rotary friction member, a non-rotary friction member to cooperate therewith, means for pressing the two friction parts together, such, for example, as a spring or weight, and manual means for actuating the pressure means arranged to be operated by the weaver without leaving her seat. The friction members may take various forms but preferably the warp roller is provided with a friction drum which serves as the rotary member and a flexible element such as a rope or chain, maintained under tension by the spring or weight, serves as the non-rotary member and is arranged to pass around and cooperate with the friction drum. The manually operable means also may take various forms but preferably a simple lever is employed, pivoted on the main frame of the loom and extending forward to a position to be readily grasped by the weaver while seated in normal working position at the front of the loom.

Another object of the invention is to provide a hand loom of the floor type having a frame of relatively light but strong and rigid construction, this object being attained by features of construction which will be hereinafter described in detail.

Other objects, more or less incidental or ancillary to those already stated, and the manner in which all of the various objects are attained will appear from the following detailed description of a loom embodying my improvements as shown in the accompanying drawings.

In the drawings,

Fig. 1 is a vertical longitudinal sectional view of the loom embodying the improvements, the section being taken on the line 1—1 of Figs. 4 and 7.

Fig. 2 is a fragmentary elevational view of the reed of the loom and of the upper part of the beater in which the reed is detachably mounted.

Fig. 3 is a fragmentary end elevation of the beater structure shown in Fig. 2.

Fig. 4 is a vertical transverse section on the line 4—4 of Fig. 1.

Fig. 5 is a fragmentary section taken on the line 5—5 of Fig. 4.

Fig. 6 is a fragmentary rear elevation of a lower portion of the loom with some of the parts shown in section.

Fig. 7 is a plan view of the loom.

Fig. 8 is a right side elevation of the loom, some of the parts being broken away.

Fig. 9 is a view similar to Fig. 1 with the sub-assembly removed.

Fig. 10 is a side elevation of the separable assembly showing parts of the assembly before they have been arranged upon the assembly frame.

5 Fig. 11 is a plan view of the assembly with the parts thereof compactly arranged on the supporting frame or structure.

Fig. 12 is a vertical sectional view of the assembly, the section being taken on the line 12—12 10 of Fig. 11.

15 Fig. 13 is an enlarged fragmentary sectional view showing the detent device which serves, in lieu of the friction brake which normally controls the warp roller, to prevent unwinding of the said roller when the assembly is detached from the main frame of the loom.

Referring in detail to the construction illustrated, the main frame of the machine comprises side sections, each of which is made up of 20 a front upright 1 and rear upright 2 rigidly joined by horizontal members 3 and 4. Members 3 and 4 support an upright 5 which is also joined to the upright 2 by horizontal member 6.

25 The two side frame sections are rigidly connected by a plurality of transverse members, one of which is in the form of a metal tube 7 and enclosed tension rod 8. The ends of tube 7 fit into circular sockets in the uprights 1, 1 and when nuts 9, 9 on tension rod 8 are tightened the 30 transverse structure effects a very rigid connection between the upper ends of uprights 1, 1. The lower parts of the same uprights are similarly connected by tube 10, tension rod 11 and nuts 12. The tube 7 serves as the front or cloth beam 35 of the loom. At its rear end the side sections are connected by tension rod 13 and nuts 14 at the upper ends of the uprights 2 and by a similar but heavier tension rod 15 near the lower ends of uprights 2, 2. Tension rod 15 is fitted at each 40 end with nuts 16, 17 and washers 18, the nuts 16 serving, in conjunction with rod 15, to accurately space the lower parts of the uprights 2, 2 from each other and nuts 17, when tightened, acting to effect a rigid connection between the 45 lower rear parts of the side sections of the frame.

The uprights 5, 5 of the frame side sections are rigidly joined by a transverse member 19 at the top of the uprights and by a transverse member 20 which joins the uprights 5 below the horizontal members 3, 3. The frame is further braced transversely by means of a metal tube 21 which fits into circular sockets in brackets 22, 22 which are rigidly secured by bolts 23, 23 to uprights 5. The brackets 22 provide bearings for 55 the trunnions 24a, 24b of the cloth roll 24 of the loom.

The rear or warp beam of the loom is formed by a transverse metal tube 25, the ends of which fit in circular sockets in depending arms 25a, 25a, the upper ends of which are pivotally mounted on the transverse rod 13. The warp beam 25, when not subjected to the tension of the warp, can be swung rearwardly and upwardly with the arms 25a about the rod 13 as an axis, as indicated by dotted lines in Fig. 1. Forward movement of the warp beam is prevented by blocks 26 secured to uprights 2 in position to be engaged by the lower ends of arms 25a.

70 The warp roller 27 of the loom is fitted at one end with a friction drum 28 and has its supporting trunnions 27a, 27a mounted in bearing blocks 29. These bearing blocks are in turn detachably mounted on a sub-frame structure designated as an entirety by 30. This sub-frame comprises fore and aft side bars 31, 31, a transverse mem-

ber 32, a flat bottom part 33, preferably made of 5 ply wood, transverse strips 34, 34 secured to the front edge of the bottom 33 and a handle bar 35 also secured to the front part of bottom 33 and spanning the opening formed in the latter 5 where its front portion is cut away at 33a. The main frame parts 31, 31 have their rear ends forked or slotted (Figs. 8 and 10) to receive the bearing blocks 29 which latter are detachably secured to the frame parts 31 by pins 36. The 10 sub-frame 30 is supported in the main frame by slide bars or ways 37 which are rigidly secured to uprights 2 and 5 of the main frame. The sub-frame and associated parts are operatively secured to the main frame by means of angle irons 15 38 which are secured to the side members 31, 31 and are apertured at 38a to receive pins or studs 39, 39 carried by uprights 2, 2. When the sub-frame 30 is slid into the main frame from the rear, angles 38 engage the uprights 2, 2 to limit 20 the forward movement of the sub-frame and gravity hooks 40, 40 mounted on uprights 2, 2 engage the upper ends of angles 38 to normally prevent rearward displacement of the sub-frame 30. A pivoted detent 41 is mounted on the trans- 25 verse frame member 32 adjacent the friction drum 28 so as to operatively engage notches 28a of the drum and prevent unwinding of the warp roller 27 when the sub-frame 30 is removed from the main frame of the machine in a manner 30 hereafter explained.

The transverse frame member 32 carries a pair of upstanding, rearwardly-bent fingers 42, 42 and an opposing pair of upstanding fingers 43, 43 are mounted on a transverse bar 44 which is yield- 35 ably secured by coiled springs 45, 45 to the front strips 34, 34 of sub-frame 30. The purpose of fingers 42 and 43 will later be explained.

To control the unwinding motion of the warp roller I provide a flexible chain, rope or the like 40 to cooperate with the friction drum 28. As shown in the drawings, the flexible friction member is in the form of a rope 46 which is fitted at its upper end with a ring 47 detachably secured to hook 48 carried by one of the stop blocks 26. 45 Rope 46 is given one turn around the drum 28 and has a ring 49 at its lower end secured to a bent finger 50 on the rear end of an elongated hand lever 51 which is pivotally supported at 52 on the main frame bar 4 at the right side of 50 the main frame. A heavy coiled spring 53 has its lower hooked end secured to transverse tension rod 15 of the main frame and its upper end secured to the bent finger 50 of lever 51. The tension of spring 53 is thus in effect applied to 55 the friction rope 46 but the operator, sitting at the front of the loom, can at any time readily relieve the spring tension of rope 46 by depressing the front end of lever 51. By disposing the end portions of rope 46 to extend from friction drum 60 28 substantially in the same plane tangent to the drum the stresses upon the supporting bearings of the warp roller are minimized.

The loom is provided with heddle devices of 65 known construction. The heddle harness is designated in its entirety by the numeral 54 and comprises four heddle frames 55, 56, 57 and 58. The front frame 55 is supported by a pair of flexible straps 59, 59 and the next frame 56 is similarly supported by straps 60, 60, the straps 70 59 and 60 having their upper ends secured to a roller 61, and being wound upon said roller in opposite directions so that as the roller turns, with the depression of one of the frames, the other frame of the pair is lifted. The roller 61 75

has its flanged ends rotatably supported in the looped ends of flexible straps 62, 62, the upper ends of which are attached to the large heddle roller 63 which has its end trunnions rotatably supported in the uprights 5 of the main frame of the loom. The rear pair of heddle frames 57 and 58 are supported by straps 64 and 65 carried by roller 66 which in turn is supported by straps 67, 67 secured to the large roller 63, the straps 62 and 67 being wound in opposite directions on roller 63 so that the lowering of roller 61 and its heddle frames 55 and 56 is accompanied by raising of the roller 66 and its heddle frames 57 and 58. The rollers 61 and 66 can readily be detached from the looped ends of straps 62 and 67 to permit removal of the heddle frames from the main frame of the machine. The heddle frames carry the usual heddle bars 68, 68 on which are mounted metal heddles 69, 69 of well known form. The raising and lowering of the heddle frames to form the shed in weaving is effected by foot treddles 70, 70 which have their rear ends pivotally mounted on transverse frame bar 15 of the main frame. Tubular spacers 15a, 15b on rod 15 space the treddles transversely by the loom. Each of the foot treddles is operatively connected to the lower side of one of the heddle frames by a rope 71, the lower end of which is fitted with a spring snap or hook 72 which detachably engages a screw eye 73 carried by the treddle. To provide a guide for the upper ends of the treddle ropes 71 transverse frame member 20 is fitted with a bracket 74 and the member 20 and bracket 74 are recessed to receive a metal sleeve 75 through which the ropes are passed.

The loom is provided with a beater which is designated in its entirety by the numeral 76. The beater comprises side bars 77, 77 which are rigidly connected by a transverse member 78 and which have their lower ends pivotally mounted in brackets 4a and 4b secured to the main frame members 4, 4. A transverse handle or grip bar 79 is detachably secured to the upper ends of the beater uprights 77, 77 and the two transverse members 78 and 79 are slotted to receive and hold a reed 80 of known or usual construction. The reed can readily be detached from the beater frame by simply removing the grip bar 79.

The cloth roller 24 of the loom is fitted at its right end with a hand operated ratchet wheel 81 which is preferably made of wood and formed with finger openings 81a so as to be conveniently grasped by the operator to turn the cloth roller in either direction. The roller is normally prevented from rotating in the unwinding direction by means of a pawl or detent 82 which is pivotally mounted in frame bracket 4a and is yieldingly pressed into operative engagement with the teeth of ratchet wheel 81 by a coil spring 83. However, the detent 82 can readily be depressed manually and held in inoperative position by a pin 84 which is adapted to engage holes in bracket 4a and detent 82, as shown in Fig. 9. The cloth roller is fitted with the usual canvas apron 85 by means of which the end of the cloth can be detachably, frictionally secured to the roller.

The manner in which my improved loom is used and operated will now be described. As those familiar with the art will appreciate from the foregoing description, the loom can be prepared for weaving in the manner usually employed with looms of the floor type. The warp w is wound upon the warp roller 21, preferably with warp sticks in accordance with the usual

practice. The winding of the roller is facilitated by the fact that its bearing 29 can readily be detached to permit the mounting of the roller in special winding apparatus, if desired. When wound, the roller is readily replaced in the loom whereupon the warp threads are passed over the warp beam 25, threaded through the heddles in a manner to produce a desired pattern, reeded in, passed over the cloth beam 7 and transverse tube 21 and attached to the cloth roller 24, in the usual manner.

The loom as shown and described contemplates the use of the usual hand shuttle and the shed is formed by depression of the foot treddles to lower and raise the heddle frames in the well known manner.

As the weaving progresses the operator is able from time to time to wind the cloth W upon the cloth roller by pressing downward on lever 51 with her left hand to ease off the braking friction on the warp drum and at the same time manipulating the ratchet wheel 81 with her right hand to wind up the cloth. This is easily and conveniently accomplished by the operator without leaving her seat.

As has been indicated, the loom is designed to permit the carrying on of a number of weaving projects during the same period of time. Assuming, for example, that the loom is being used in a school or other institution where it is desired that a number of persons may use the loom for their respective projects, when one of the weavers has completed her weaving session she proceeds to remove her own work from the loom and prepare it for another user in the following manner.

First, the operator steps to the rear of the loom and throws the detent 41 backward into operative engagement with the notches 28a of the friction drum 28 of the warp roller. This prevents unwinding of the roller. The rear end of lever 51 is then lifted against the tension of spring 53 to permit the top ring 47 of the friction rope 46 to be detached from its hook 48 so that the rope is no longer effective. The operator then unhooks the treddle ropes 71 from the treddles 70.

Next, the detent 82 of ratchet wheel 81 is locked down in inoperative position by the use of pin 84. This permits the unwinding of the cloth roller 24 and the detachment of the wound cloth therefrom. Then the top bar 79 is lifted off the beater 76 so that the reed 80 can be detached from the beater. The operator now detaches the small heddle rollers 61 and 66 from the loops of their respective supporting straps 62 and 67 whereupon the said heddle rollers 61 and 66, the four heddle frames and their heddles, the reed and the woven cloth are lifted free of the other parts of the loom and carried backward over the warp beam 25 so that the latter

can be swung upward out of the way while the separated parts are assembled upon the tray-like sub-frame 30 of the loom. The operator can retain the warp beam 25 in its elevated position by laying a shed stick or the like across the rear tension rod 13 and one of the side bars 6 of the loom frame to serve as a support. Preferably the woven cloth is first folded upon the sub-frame bottom 33 and the reed is laid upon it.

Then the lower bars of the heddle frames are placed over the hooks 43 of the sub-frame and the heddle rollers 61 and 66 are pulled rearward against the tension of coiled springs 45 to permit the said rollers to pass over the upstanding hooks 42, 42 so that the heddle harness is held yieldingly but firmly in position on the sub-frame, the hed-

75

idle harness parts holding the cloth, reed, etc., in position.

The operator may now throw the gravity hooks 40 upward to inoperative position and slide the 5 entire separable assembly rearward and out of the main frame of the loom. Fig. 10 shows what may be termed an expanded side elevation of the sub-frame, the heddle harness, the reed and the cloth—in other words, the parts constituting the 10 removable sub-assembly. Figs. 11 and 12 show 15 in plan and section, respectively, the parts of the sub-assembly with the cloth, reed and heddle harness in their compact, secured position on the sub-frame. Fig. 9 shows in vertical section the 15 main frame parts as they appear after removal of the sub-assembly.

The main frame of the machine is now ready to be used by another weaver and to receive a sub-assembly or insert of the same character as that 20 which the first weaver has removed. As will readily be understood, the insertion of the second sub-assembly is effected by carrying out in reverse order the above described steps of removal of the first sub-assembly. The second sub-assembly 25 frame is first slid into position in the main frame and secured by the gravity latches or hooks 40. To facilitate detachment of the heddle harness, etc. from the sub-assembly frame, the warp beam 25 may be swung upward and secured in 30 elevated position as previously described. The heddle harness parts are then detached from the hooks 42 and 43 of the sub-frame, the loose ends of the heddle ropes are put through the guide sleeve 75, the heddle rollers 61 and 66 are attached to their respective supporting straps, the reed is reinserted in the beater and the cloth carried over the cloth beam 7. Next, the friction brake rope 46 is replaced upon the friction drum, the detent 41 is thrown forward to inoperative 40 position, the pawl 82 is released to engage the ratchet wheel 81 of the cloth roller, and the cloth is operatively attached and wound up on said roller. Finally, the treddle ropes are attached to the foot treddles, and the operator is ready to 45 proceed with her weaving projects. During the weaving the sub-frame 30, by reason of its tray-like form, serves as a convenient support for the weaver's supplies and auxiliary implements. When the weaver has finished her period of weaving 50 she removes the sub-assembly which she had inserted at the beginning, leaving the main frame of the loom ready for the next weaver.

As soon as a weaver becomes familiar with the construction and operation of the loom she is able 55 to insert her sub-assembly into the main frame of the loom at the beginning of her weaving and to remove it at the end of her weaving in a total time of only three or four minutes.

In practice I provide sectional storage cabinets 60 for the sub-assemblies or inserts, each operator or weaver using the loom having one of the dust-proof cabinet sections assigned to her for the storage of her sub-assembly or insert. These cabinet sections are fitted with lock-controlled doors 65 or closures and are adapted to be stacked one upon the other after the manner of sectional book cases. With this type of equipment a single loom and set of sub-assemblies or inserts can easily be made to serve a class of ten weavers, thus reducing 70 the floor space required to that necessary for a single loom and two stacks of cabinet sections. Furthermore, the cost of such an equipment is much less than the cost of the number of complete looms which would be necessary to serve the 75 same number of student weavers.

It will be apparent that the improved friction brake and control devices for the warp roller is not limited in its application to looms having my improved detachable inserts. Similarly the tubular metal cross beam type of construction is 5 obviously applicable to looms constructed in a variety of ways, as are also other features of the construction disclosed. In general, it should be understood that my improvements are not limited to the specific construction shown and described 10 but that the scope of the invention is indicated by the appended claims read in accordance with the established rules of construction.

What I claim is:

1. In a loom, the combination of a main frame 15 structure; shed forming devices comprising heddles and heddle supporting means operatively mounted on the main frame so as readily to be detached therefrom; a beater operatively mounted on the main frame; a reed detachably mounted on the beater; a warp roller; and a sub-assembly frame upon which the warp roller is operatively mounted, the latter frame being detachably mounted upon the main frame and constructed to support the heddles, heddle supporting means and reed together with any work in progress in the loom, whereby the sub-assembly frame, warp roller, heddles, heddle supporting means, reed and work can be removed as a unitary sub-assembly from the main frame to permit the insertion in the main frame of another 30 similar sub-assembly.

2. A loom as claimed in claim 1 in which the heddle supporting means comprises a plurality of 35 heddle frames.

3. In a loom, the combination of a main frame structure; shed forming devices comprising heddles, heddle frames operatively mounted for up and down movement on the main frame and so as readily to be detached therefrom, and means 40 for raising and lowering the heddle frames comprising foot treddles and ropes connecting together the treddles and the heddle frames, each rope being readily detachable from its treddle; a beater; a reed detachably mounted on the 45 beater; a warp roller; and a sub-assembly frame upon which the warp roller is mounted, the latter frame being detachably mounted upon the main frame and constructed to support the heddles, heddle frames, treddle ropes and reed together with any work in progress in the loom, whereby the sub-assembly frame, warp roller, heddles, heddle frames, treddle ropes, reed and work can be removed as a unitary sub-assembly from the main frame to permit the insertion in 50 the main frame of another similar sub-assembly.

4. A loom as claimed in claim 1 in which the sub-assembly frame is provided with a detent device to engage the warp roller structure and prevent unwinding of the warp roller while the sub-assembly is separated from the main frame of the loom.

5. In a loom of the hand operated type, the combination of a frame adapted to support the working parts of the loom; a warp roller operatively supported on the rear part of the frame; and means for controlling the rotation of the roller comprising a friction member rotatable with the roller, a non-rotary friction member arranged to engage the other friction member, a 70 spring for forcing the two friction members into mutual frictional engagement, and manually operable force-transmitting means connected to said spring and adapted to oppose the force exerted thereby upon the said friction members, 75

said manual means being mounted on the frame and extending to the front part of the frame, whereby the frictional resistance opposed to the rotation of the warp roller can be varied by the 5 weaver while seated in normal working position at the front of the loom.

6. In a loom of the hand operated type, the combination of a frame adapted to support the working parts of the loom; a warp roller operatively supported on the rear part of the frame; and means for controlling rotation of the roller comprising a friction drum attached to one end of the roller, an elongated flexible friction member looped around the friction drum and having 10 one of its ends attached to the frame, a lever operatively mounted on the frame and connected to the other end of the flexible friction member and extending forward in a position to be actuated by the weaver seated at the front of the 15 loom, and a spring attached to the frame and connected to the lever and flexible friction element, whereby the tensional force applied by the spring to the flexible friction element can be opposed and varied by movement of the lever.

7. In a loom of the hand operated type, the combination of a frame adapted to support the working parts of the loom; a warp roller operatively supported on the rear part of the frame; a cloth roller operatively supported on the front 20 part of the frame; a wheel on one end of the cloth roller manually operable to turn the cloth roller; and means for controlling rotation of the warp roller comprising a friction member rotatable with the said roller, a non-rotary friction 25

member arranged to engage the other friction member, a spring for forcing the two friction members into mutual frictional engagement, and manually operable force transmitting means connected to said spring and adapted to oppose the 5 force exerted thereby upon the said friction members, said manual means being mounted on the frame and extending to the front part thereof adjacent the wheel on the cloth roller, whereby the weaver while seated in normal working position at the front of the loom can with one hand release the frictional resistance to unwinding of the warp drum and with the other hand simultaneously turn the cloth roller.

8. In a loom, the combination of a frame for supporting the working parts of the loom; a warp roller; bearing means for rotatably supporting the roller on the frame; and means for controlling rotation of the roller comprising a friction drum attached to one end of the roller, an elongated 10 friction member looped around the drum and having one of its ends attached to the frame, a coiled spring having one of its ends connected to the other end of the flexible member and its other end connected to the frame so as to establish tension in the flexible friction member, the end portions of the flexible friction member being disposed to extend from the drum substantially in the same plane tangent to the friction surface of the drum engaged by the flexible member; and manual means operatively connected with the 15 frame for opposing the tension force of the spring on the flexible member.

MILO O. GALLINGER.
